UNITED STATES PATENT OFFICE.

FRANK M. HURLEY, OF BLISSFIELD, OHIO.

MAIL RECEIVING AND DELIVERY APPARATUS.

No. 821,941.

Specification of Letters Patent.

Patented May 29, 1906.

Application filed September 14, 1905. Serial No. 278,478.

To all whom it may concern:

Be it known that I, FRANK M. HURLEY, a citizen of the United States, residing at Blissfield, in the county of Coshocton and State of Ohio, have invented certain new and useful Improvements in Mail Receiving and Delivery Apparatus, of which the following is a specification.

The object of this invention is to provide an improved mail-bag delivering and receiving apparatus by which the mail-bags can be delivered and received at the same time from a rapidly-moving train and which is so constructed that the parts will automatically swing away from the track or that part of the mechanism which is located alongside of the same.

The invention consists, broadly speaking, in the provision of a post alongside of the track, said post supporting both a hook for receiving a mail-bag from a train and also supporting devices for holding a mail-bag so that the train may catch one bag while it is delivering another and a complementary device carried by the train for coacting with the device supported along the track.

For a full description of the invention and the merits thereof and also to acquire a knowledge of the details of construction of the means for effecting the result reference is to be had to the following description and accompanying drawings, in which—

Figure 1 is a perspective view showing the invention applied. Fig. 2 is a detail perspective view of the car device with parts separated. Fig. 3 is a plan view of the top bar of the car device. Fig. 4 is a detail section on the line $x-x$ of Fig. 3. Fig. 5 is a vertical section of the post-arms in full lines in inoperative position and dotted in operative position. Fig. 6 is a detail perspective view of the post. Fig. 7 is a detail horizontal section of the post.

Corresponding and like parts are referred to in the following description and indicated in all the views of the drawings by the same reference characters.

At the desired point along the track is mounted a post 1. It is provided at a suitable point in its height with a base portion 2, from which downwardly-extending beveled surfaces 3 extend. Above the base 2 the post is preferably made cylindrical in cross-section throughout the rest of its length, as shown at 4. On the lower end of its cylin-

drical portion 4 is mounted a sleeve 5 in such a manner that it may move freely both axially and in a vertical direction. The sleeve 5 carries a hook 6, which is designed to catch a mail-bag from the train in the usual manner, and said hook is preferably pivotally connected to the sleeve 5 so as to turn axially and may be secured to the sleeve by a pin-and-socket connection 6^a in either a right-hand or left-hand position, according to the direction in which it is desired said hook shall face. The sleeve 5 is provided with a downwardly-extending foot 7, that is designed to normally rest on the base 2, and in this position the sleeve is at the upward limit of its movement and the hook projects out toward the track. Above the sleeve the post 1 carries a stop 8, which may be secured in two diametrically opposite positions by means of a pin-and-socket connection or some suitable device in order that the downwardly-extending finger 10 thereof may lie on one side or the other of the sleeve 5. This finger 10 is designed to limit the movement of the sleeve 5 in one direction. When the hook 6 is in operative position, as illustrated in Fig. 6, with the extension 7 resting upon the base 2, it is in position to catch a mail-bag. As the train approaches and the vertically-supported bag is held out therefrom it will be caught in the angle of the hook and detached from its supporting-arms, and at the same time the impact will cause the hook to swing axially, which will in turn cause the foot or extension 7 to be forced off the base 2 and to ride downwardly upon one of the oblique surfaces 3. Hence the bag will be carried away from the track and also lowered into a convenient position to be detached from the hook. If desired, the hook 6 may be provided with a locking-arm 11, which, as illustrated in the drawings, is in the form of a lever fulcrumed thereon to move in a plane coincident with the prongs of the hook.

The locking-arm 11 is mounted to turn freely on its pivot on the hook 6. It is provided with two angularly-disposed arms and is pivoted at the junction of said arms, and its normal receiving position with respect to the hook 6 is illustrated in Fig. 7. When the mail-bag enters the said hook, it will strike against that arm of the part 11 which extends across the members of the hook and will thereupon turn the part 11 so that the other arm thereof will be turned into a posi-

tion back of the bag, and thereby prevent it from accidentally falling away from the hook. It is to be understood that while the hook is lowered, as it is turned away from the track, 5 the lower limit of its movement is at such elevation that it will clear the ground or platform. Above the catching device just described there is mounted a holding device. This consists of two arms, the lower- 10 most of which (designated 12) is mounted to freely turn on the post in an axial direction and is also free to move up and down within certain limits. At its inner end it is provided with a downwardly-extending foot 13, 15 designed to rest on a sleeve 14, rigidly secured to the post or formed therewith, if desired, and the sleeve 14 is provided with a flat portion 15, from which descends surfaces 16, so as to hold the lower part 12 projecting 20 out toward the track at the highest point of elevation, also to allow said lower member to descend as it is swung around, the foot 13 riding on the surfaces 16 in a manner similar to that before described with respect to the 25 foot 7 and surfaces 3. Above this lower member the post is provided with a collar 17, which limits the upward movement of the lower member 12. At the upper end of the post, and preferably at the extremity there- 30 of, the uppermost member 18 of the holding device is mounted. This member is supported on the post to swing in a vertical plane, so that it may rest with its free end projecting toward the track to coact with the lowermost member 12 or may be turned 35 backwardly, as indicated in the drawings, so as to rest out of the way. It is thrown backwardly automatically by means of a spring 19 from its forward position when it is co- 40 acting with the lowermost member 12. This spring is held under tension, as will be readily understood. Both the member 12 and the member 18 are provided at their free ends with fingers 20, pivotally supported thereon 45 and preferably constructed of spring-steel or some similar suitable material. These two fingers are designed to hold the mail-bag in vertical position between them, and any number of such bags may be thus held, it being 50 my intention to provide the mail-bags with loops or eyes 21 at both upper and lower ends for the reception of the fingers 20. In the operation of this part of the apparatus, the mail-bag being held between said fingers 55 out toward the track, as the train approaches the hook projecting outwardly therefrom will engage the bag, and as it does so and disengages it from the fingers the impact will force the lowermost member 12 backwardly 60 and downwardly, while at the same time the uppermost member 18 being freed will be thrown over backwardly by its spring, so as to be out of the way.

The above-described mechanism constitutes a device for holding and delivering

mail-bags at the desired point along the track. With said device complementary devices on the car are designed to coact. The car device comprises two arms 22, an upper and a lower arm, each preferably mounted 70 or supported on a cross-bar 23 24. The arms 22 are provided at their pivoted portions with a predetermined number of sockets 25, any one of which may receive the nose of a spring-held dog 26, so as to hold the 75 arms at different positions either within or without the plane of the car. At their free ends these arms are provided with pivoted fingers 27, which are preferably constructed of spring-steel or other suitable material and 80 are, like said supporting arms, provided with sockets 28 for the reception of spring-pressed dogs 29, so that the fingers may be held in different angular relation to their supporting-arms. These two arms 22 constitute, with 85 their concomitant parts, the means for holding the mail-bag outwardly from the car in position to be caught by the hook 6.

Above the arms 22 there is mounted on a cross-bar 30 a hook 31, which is capable of 90 being turned axially within bearings 32 and is held with its prongs facing in one direction or another by means of a pivoted catch 33, entering in the rear end of the shank of the hook and pivoted at a point above the bar 95 30. The cross-bar 30 is mounted to turn upon its longitudinal axis, so that the hook may be carried bodily out of the car in a position to catch the mail-bag or inside the car when it is not desired or after it has caught 100 the bag. The cross-bar 30 is provided with a forked latch 34, by which it may be locked in different positions. As the hook catches the mail-bag the attendant within the car may readily rock the supporting cross-bar 105 and swing the hook, with its bag, into the car by pulling on the handle of the pivoted catch 33 to deposit the bag inside the car. It is obvious that the receiving and delivering mechanism for the car may be placed or 110 mounted on the door-frame or at any suitable portion of the car.

To protect the track device from the weather, the post 1 may be provided with any suitable form of housing, which must be of an 115 insufficient extent to interfere with the proper movement of the parts.

The operations of the various parts of my improved apparatus have been serially described and are obvious. It will be seen 120 that I have provided a simple and efficient mechanism for passing mail-bags to and from a rapidly-moving train and that the construction of my apparatus does not necessitate any radical departure from the system 125 now in use, but is applicable to all conditions.

Having thus described the invention, what is claimed as new is—

1. In an apparatus of the character de- 130

scribed, a supporting-post, a sleeve mounted to move freely on said post both in an axial and vertical direction, the post being provided with a base and surfaces descending therefrom, and the sleeve being provided with a foot designed to rest on said base and ride downwardly on said surfaces, and a bag-catching hook carried by the said sleeve.

5 2. In an apparatus of the character described a supporting-post provided with a base and surfaces descending therefrom, a sleeve mounted to move freely both axially and in a vertical direction on said post and provided with a foot designed to rest on said base and ride on said surfaces, and a bag-catching hook carried by said sleeve and axially adjustable thereon.

10 3. In an apparatus of the character described, a supporting-post provided with a base and surfaces descending therefrom, a sleeve mounted to move freely both axially and in a vertical direction on said post and provided with a foot designed to rest on said base and ride on said surfaces and a bag-catching hook carried by said sleeve and provided with an arm for supporting the bag thereon.

15 4. In an apparatus of the character described a supporting-post provided with a base and surfaces descending therefrom, a sleeve arranged to turn freely on said post both axially and in a vertical direction and provided with a foot designed to rest on said base and ride on surfaces, a bag-catching hook carried by said sleeve, and a stop for preventing the movement of said parts in one direction.

20 5. In an apparatus of the character described, a supporting-post provided with a base and surfaces descending therefrom, a sleeve arranged to turn freely on said post both axially and in a vertical direction and provided with a foot designed to rest on said base and ride on said surfaces, a bag-catching hook carried by said sleeve, and an adjustable stop for preventing the movement of said parts in one direction.

25 6. In an apparatus of the character described, the combination of a supporting-post, a bag-catching hook designed to swing axially around said post and to move vertically upon the same, and a stop mounted on the post and arranged to prevent or limit the movement of said hook in one direction.

30 7. In an apparatus of the character described a supporting-post and a bag-delivering device supported thereon, the same consisting of a lower member movable both axially and vertically on said post, and an upper member mounted on said post to swing in a vertical plane.

35 8. In an apparatus of the character described, a supporting-post, a bag-delivering device mounted thereon, the same consisting of upper and lower members designed to hold

the mail-bag, the lowermost being mounted to turn axially and also to move in a vertical direction, and said member being provided with a foot, and the post provided with inclined surfaces designed to effect a turning and lowering of said member.

7c 9. In an apparatus of the character described, a supporting-post and a bag-delivering device carried thereby, the same comprising a lower member and an upper member, the latter of which is mounted on the post to swing in a vertical plane, a tension device for said upper member and means whereby in the operation of securing the mail-bag to said members, said tension device will be compressed in condition to automatically throw back said upper member when the bag is released therefrom.

75 10. In an apparatus of the character described a bag-holding device for the car comprising arms mounted to swing in a horizontal plane and pivoted fingers supported on said arms and designed to hold between them the mail-bag, each of said fingers being provided with means whereby it may be locked in different angular positions with respect to its arm.

80 11. In an apparatus of the character described a bag-holding device for the car comprising arms, bag-holding fingers pivotally mounted on the free ends of said arms and each of said fingers being provided at its pivot portion with a plurality of sockets, a dog designed to enter said sockets whereby to lock the fingers in different angular positions with respect to the arms.

85 12. In an apparatus of the character described, a bag-catching device for the car, the same comprising an axially-rotatable support or bar provided with a bearing, a hook mounted with its shank rotatable in said bearing and said shank provided on its rear end with a bifurcated extension, an arm or lever carried by said bearing and designed to enter said extension to hold the hook in different positions.

90 13. In an apparatus of the character described a supporting-post provided with a base and inclined surfaces descending therefrom a sleeve mounted to turn freely on said post both axially and in a vertical direction and provided with a foot designed to rest on said base and ride on said surfaces, a bag-catching hook carried by said sleeve and a stop mounted on said post above said sleeve and provided with a downwardly-extending finger designed to lie on one side or the other of said sleeve whereby to prevent movement of the said sleeve in one general direction.

95 14. In an apparatus of the character described, a supporting-post and a bag-delivery device supported thereon, the same comprising a lower member designed to hold the lower end of the bag, and an upper member designed to coact with the lower member, the

- upper member being hinged at the upper end of the said post and arranged to lie thereon, and a spring secured to the upper end of said post and arranged to be compressed by the 5 said upper member when the latter is projected from the upper end of the post where- by when the bag is released the said spring will throw said upper member backwardly from the post into an inoperative position.
- 10 15. In an apparatus of the character de- scribed, a bag-catching device comprising a supporting-bar mounted to rotate about its longitudinal axis, a hook mounted on said bar and axially turnable thereon, and an arm 15 or lever 33 pivotally carried by said bar above the same and provided with a handle de- signed for locking engagement with the shank of the hook, whereby said arm or lever performs the double function of locking the 20 hook in an axially-disposed position and serving as a handle which the operator may

grasp to rock the support and swing the hook backwardly into the car.

16. In an apparatus of the character de- scribed, a bag-catching device for the car 25 comprising a support in the form of a rota- table cross-bar, a hook having its shank mounted to turn axially on said cross-bar at right-angles to the movement thereof, and a pivoted arm 33, provided with a handle por- 30 tion designed to enter the shank of the hook whereby to hold the latter in different ad- justed positions with respect to its support- ing-bar; said handle also serving as means whereby the operator may rock the bar and 35 turn the hook bodily backward into the car.

In testimony whereof I affix my signature in presence of two witnesses:
